US00D769690S

(12) **United States Design Patent** (10) **Patent No.:** **US D769,690 S**
(45) **Date of Patent:** **** Oct. 25, 2016**

(54) **COMBINATION FASTENER AND MATING
DRIVING TOOL**

(71) Applicant: **Bryce Fastener Company, Inc.**,
Gilbert, AZ (US)

(72) Inventor: **Richard Bryce Campbell, II**, Gilbert,
AZ (US)

(73) Assignee: **Bryce Fastener Company, Inc.**,
Gilbert, AZ (US)

(**) Term: **15 Years**

(21) Appl. No.: **29/531,456**

(22) Filed: **Jun. 25, 2015**

Related U.S. Application Data

(63) Continuation of application No. 14/729,367, filed on
Jun. 3, 2015, which is a continuation-in-part of
application No. 13/891,521, filed on May 10, 2013.

(57) **CLAIM**

The ornamental design for a combination fastener and
mating driving tool, as shown and described.

DESCRIPTION

FIG. 1 is a perspective view of a six fin driving tool;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a perspective view of a fastener having six recessed
receiving areas;

FIG. 8 is a side view of the fastener in FIG. 7, wherein the
opposite side, front, and rear views are identical; and,

FIG. 9 is a top view of the fastener shown in FIG. 7.

The broken lines in the drawings illustrate portions of the
combination fastener and mating driving tool that form no
part of the claim.
